UNITED STATES PATENT OFFICE.

CHARLES FISHER, OF CHICAGO, ILLINOIS, ASSIGNOR TO THE AUTOMATIC RECORDING
SAFE COMPANY, OF CHICAGO, ILLINOIS, A CORPORATION OF ILLINOIS.

SAVINGS BANK.

Application filed October 25, 1923. Serial No. 670,784.

This invention relates particularly to small portable savings banks; and the primary object is to provide a simple device of this character which can be cheaply manufactured, which is well adapted to its purpose, and which is readily embodied in a design of pleasing appearance.

The invention is illustrated in its preferred embodiment in the accompanying drawing, in which—

Fig. 1 represents a side elevational view of the improved savings bank; Fig. 2, a front elevational view; Fig. 3, a rear elevational view, a portion of the name-plate being broken away; Fig. 4, an inner or rear face view of the closure, removed from the casing; Fig. 5, a rear face view of an inner guard-equipped plate (shown detached) which in assembled position is secured within the cap-like member which constitutes the main member of the closure; Fig. 6, a plan view of the member shown in Fig. 5; Fig. 7, a front face view of the guard-equipped plate shown in Fig. 5; Fig. 8, an enlarged broken sectional view taken as indicated at line 8 of Fig. 2; Fig. 9, a view of the key which serves to unlock and remove the closure; Fig. 10, a broken sectional view taken as indicated at line 10 of Fig. 11; Fig. 11, a broken front elevational view of the casing, with the closure removed; Fig. 12, a broken sectional view taken as indicated at line 12 of Fig. 3, illustrating the manner in which the finishing plate, or name-plate is attached to the rear end of the casing; and Fig. 13, a broken section taken as indicated at line 13 of Fig. 5.

In the preferred construction illustrated, the savings bank comprises a cup-like shell, or main casing-section, A, and a removable closure, or casing-section A', which comprises the main cap-like end member A², and an associated guard plate A³. Confined between the front wall afforded by the member A² and the inner plate A³, is a leaf spring A⁴ which constitutes a slot-guard.

The main casing-section A comprises a cylindrical wall 1 and an end wall 1^a. This member preferably is formed from a disc of sheet metal, such as brass, and preferably has the end wall 1^a struck inwardly, thus leaving a circumferential bead 1^b at the junction of the cylindrical wall 1 with the end wall 1^a. Thus, there is provided a circular recess adjacent the end wall which receives

a finishing plate, or name-plate 2. The plate 2 is provided at its circumference with integrally formed clenching lugs 2^a which extend through slots 3 in the wall 1^a and are clenched on the inner surface of the wall 1^a, as shown in Fig. 12.

The cap member A², which constitutes the main member of the closure and affords a front wall for the casing preferably is formed from a sheet metal disc, which is shaped to provide a cylindrical flange 4 adapted to fit within the open end of the casing-section A. In forming the cap member A², it is preferred to upset the flange 4 and form a circumferential bead 5 at the junction of the end wall and the flange 4, the bead 5 projecting beyond the outer surface of the cylindrical wall of the casing-section A. Thus, one point on the bead 5 may serve as one of the supports of the savings bank, as appears from Fig. 1, and the rear surface of the bead also serves as a shoulder forming a joint with the front edge of the circumferential wall afforded by the casing-section A. The casing-section A preferably is provided near the rear end of the member with short legs which terminate in balls 6. The supports 6 are placed on opposite sides of the central vertical plane of the savings bank, and with the bearing point of the flange 5, form a tripod rest for the savings bank.

The end wall of the member A² is provided with a coin-slot 7, a bill-slot 8, and a keyhole 9. At the slot 7, the metal is struck inwardly to afford short inturned flanges 7^a. At the key opening 9, the metal is forced inwardly to form a circular embossment 9^a.

The inner member, or guard plate, A³, preferably comprises a disc of sheet metal which is provided with rearwardly turned segmental flanges 10. The upper portion of the disc is provided with an extension which, as shown, is bent rearwardly and inclined downwardly somewhat, thus affording the guard-flange 11. Beneath this flange is a transverse slot 12, which is of ample size to permit the flanges 7^a to project thereinto. Below the slot 12, the metal of the disc is struck rearwardly at an intermediate point, thus affording an inclined embossment 13 which affords a housing which permits play of the upper end of the spring-guard A⁴. Near the lower edge of the disc, the metal is

struck rearwardly, forming a rearwardly projecting circular embossment 14, which is provided with a key-slot 14^a.

The spring-guard A⁴ is in the form of a flat strip of spring metal, which is provided at its lower end with a circular perforation 15 which fits on the embossment 9^a and has extending from its upper side a short slot 15^a, adapted to admit the bit of the key.

In assembling the parts, the spring A⁴ is interposed between the members A² and A³, and portions of the rearwardly extending flange 4 of the member A² are bent or crimped over the rear edges of the segmental flanges 10 of the member A³, as indicated at 4^a. The spring A⁴ normally bears against the lower flange 7^a of the coin-slot 7, and the upper end of the spring serves as a guard for the coin-slot. The guard member 11 projects rearwardly over the housing member 13 a sufficient distance to guide bills inserted through the bill opening 8 over the slot-guard A⁴. The member 11 also serves to prevent tampering with the slot-guard, as by the insertion of an instrument through the opening 8.

The preferred manner of securing the closure in position is to provide the circumferential wall of the casing-section A near the front edge of the upper portion with a stud 16 which engages a perforation 16^a in the flange 4; and to equip the casing-section A at its lower portion with a spring latch or locking member 17 which has a catch portion 17^a in the form of a hook which is adapted to engage an upturned lip 4^b with which the flange 4 is provided at its lower portion. The member 17 is in the form of a strip of spring metal whose rear end portion is secured, by rivets 18, to the circumferential wall of the casing-section A. The front portion of the member 17 extends through a yoke 19 which is secured to the circumferential wall of the casing-section A by rivets 19^a. The front end of the member 17 is provided with an arm 17^b which is bent upwardly and then extended forwardly to provide a lug 17^c which is adapted to be struck by the bit of the key when the key is inserted through the key-slot and turned. The key is designated 20, and is provided with a bit 20^a, which, as indicated by the dotted lines in Fig. 11, is adapted to engage the lug 17^c to retract the locking member 17. When the key is in the rotated position indicated by the dotted lines, the hook or latching lip 17^a is withdrawn from engagement with the lip 4^b, and the key may then be employed to withdraw the closure. The lips 4^b and 17^a are so formed, as appears from Fig. 9, that when the closure is applied, the latching will take place automatically. The loop 19 serves to limit the lifting movement of the member 17, so that the key cannot be turned beyond the amount requisite for lifting the

member. This is to insure the disengagement of the latch while the key is being employed as a means for withdrawing the closure.

The construction described is simple, cheap, and thoroughly effective for its purpose. Moreover, it enables an embodiment of very pleasing design to be given to the invention. In the operation of inserting a coin through the slot 7, the upper end of the spring-guard A⁴ is moved rearwardly in the housing 13 until the coin passes the upper flange 7^a, after which the spring snaps back to the position shown in Fig. 8. In the illustration given, the lower end portion of the spring is clamped between the end wall of the cap member A² and the guard member A³. To additionally secure the spring in position, the metal at the base portion of the housing 13 is struck forwardly and partially sheared, thus forming clinching lugs 21 which engage the lateral edges of the clamped portion of the spring, as shown in Fig. 13, thus preventing possibility of the spring turning about the embossment 9^a.

The foregoing detailed description has been given for clearness of understanding only, and no unnecessary limitations should be understood therefrom, but the appended claims should be construed as broadly as permissible in view of the prior art.

What I regard as new, and desire to secure by Letters Patent, is:

1. A savings bank comprising a casing-section having an open end, a closure having a flange extending into said open end and having an end wall provided with a key-slot and with a coin-slot, stud and slot connection between said casing-section and said flange at one point, a locking member mounted in the casing and engaging said flange at another point, a guard plate adjacent the inner surface of the end wall of said closure, said guard plate having rearwardly extending flanges, the flanges of said members being secured together, and a leaf spring confined between the end wall of said closure and said guard plate and having a free end serving as a guard for said coin-slot.

2. A savings bank comprising an open ended casing-section, and a removable guard-equipped closure comprising a closure cap having a rearwardly extending flange, said closure cap being provided with a coin-slot and being provided also with a key-slot and an inwardly extending embossment at said key-slot, a guard plate provided with a key-slot and with a slot-guard housing, a leaf spring interposed between the closure cap and guard plate and having at one end a perforation engaging the embossment at the key-slot in the closure cap, the free end of said spring extending into the path of a coin inserted through said coin-slot, means securing the guard plate to the closure cap,

and a locking member mounted in said casing-section and releasably engaging a part carried by said closure cap.

3. A savings bank comprising an open ended casing-section equipped at one side with an internal stud and at the other side with a longitudinal spring member affording a locking member, and a guard-equipped closure comprising a closure cap having a flange provided with a perforation engaging said stud and having a locking lip engaging said locking member, said closure cap being provided at its upper portion with a bill-slot, at an intermediate portion with a coin-slot, and at its lower portion with a key-slot, a guard plate having flanges secured to the flange of said closure cap and having also a top flange disposed above the coin-slot, and a leaf spring interposed and secured between said closure cap and said guard plate and having its upper end extending over the coin-slot and free to move to admit a coin.
4. A savings bank comprising an open ended casing-section equipped internally with locking means, and a guard-equipped closure comprising a closure cap having a flange adapted to enter said casing-section and having an end wall provided with a bill-slot at one point, with a coin-slot at another point, and with a key-slot at another point, said end wall having internal embossments at the coin-slot and key-slot, a guard plate having a flange disposed above the coin-slot, having also a slot-guard housing; and having an embossment provided with a key-slot, said guard plate being secured within

the flange of said closure cap, and a leaf spring confined between the end wall of said closure cap and said guard plate, said spring having a perforation engaging the embossment at the key-slot with which said closure cap is provided and having a free end extending over the coin-slot, the free end portion of the spring bearing on the embossment at the coin-slot.

5. A savings bank comprising a cup-shaped casing-section adapted to rest on one side, a longitudinally disposed spring member secured within said casing-section at the lower side thereof and equipped with a locking lip and a key engaging arm, and a guard-equipped closure comprising a closure cap having a flange extending into said casing-section and equipped with a locking lip, said closure having an end wall provided at its upper portion with a bill-slot, at an intermediate portion with a coin-slot, and at its lower portion with a key-slot and an inner embossment at said key-slot, a guard plate having a rearwardly projecting upper flange disposed above the coin-slot, and having an intermediate guide for a spring guard, and having a lower portion provided with a key-slot registering with said first named key-slot, means securing said guard plate within the flange of said closure cap, and a leaf spring having its lower end portion anchored between the end wall of said closure cap and said guard plate and having its upper end extending over the coin-slot and free to work in said guide.
